UNITED STATES PATENT OFFICE

2,337,140

THERMOCOUPLE OPERATED ELECTRO-MAGNET

Theodore A. Wetzel, Milwaukee, Wis., assignor to
Milwaukee Gas Specialty Company, Milwaukee, Wis., a corporation of Wisconsin

Original application June 16, 1937, Serial No. 148,495, now Patent No. 2,267,775, dated December 30, 1941. Divided and this application November 21, 1941, Serial No. 419,993

3 Claims. (Cl. 175—336)

This invention relates to improvements in thermocouple operated electromagnets, and has particular reference to improvements in thermocouple operated electromagnets for controlling the supply of gaseous fuel to gas burners and the like.

The present application is a division of my co-pending application Serial No. 148,495, filed June 16, 1937, now Patent No. 2,267,775.

In its preferred embodiment, the thermocouple operated electromagnet of the present invention comprises an electromagnet having a magnet frame and a coil. The main burner is provided with a pilot burner for lighting the same, and a thermocouple provided with a hot junction responsive to the heat of the pilot flame is connected to the coil of the electromagnet. The heat of the pilot flame generates a thermoelectric current in the thermocouple, and this thermoelectric current energizes the electromagnet. The electromagnet has an armature which acts to close and hold closed a circuit for an electrically operated valve in the gas supply pipe for the main burner when the electromagnet is energized by the thermoelectric current generated by the heat of the pilot flame.

Closing of the circuit for the electrically operated valve opens this valve to set up and maintain the desired supply of gaseous fuel to the main burner so long as the pilot burner is lighted. If the pilot burner is extinguished, the thermoelectric current ceases, and the electrically operated valve operates to closed position to shut off the supply of gaseous fuel to the main burner.

A thermoelectric current generated by the heat of a pilot flame has heretofore been used to control an electrically operated valve in the gaseous fuel supply line for the main burner independently of an auxiliary source of current such as house current or battery, but heretofore the thermoelectric switches have usually been operable only to hold the circuit for the electrically operated valve closed and have been incapable of operating the switch to close said circuit by means of the relatively weak thermoelectric current produced by the heat of the pilot flame. As a result, resetting devices have been required for resetting the thermoelectric switch to closed position.

These resetting devices usually move the armature into contact with the magnet frame of the electromagnet, and, simultaneously, the switch contact means to closed position. If the resetting device is operated to close the thermoelectric switch and thereby the circuit for the electrically operated valve in the fuel supply line, the elec-

cally operated valve will open, and if the pilot burner is not lighted gaseous fuel will flow to the main burner and escape and collect unburned. This unburned gas presents the danger of possible explosion when a flame is applied to light the pilot burner, and also the possibility of asphyxiation.

One of the main objects of the present invention is to provide a thermoelectric switch which not only is adapted to be held closed by a relatively weak thermoelectric current, but is also adapted to be actuated to closed position by such a current without resetting devices or other auxiliary means for closing the switch.

It is also an object of the invention to provide an improved reaction spring and armature assembly for securing in a thermoelectric switch operated by a relatively weak thermoelectric current not only the desired operation as above set forth, but also a mechanical snap action which will produce a sharp, clean interruption of the current in the circuit controlled by the thermoelectric switch.

It is to be understood, however, that the thermoelectric switch of the present invention is not limited to use with circuits requiring a snap action or sharp, clean interruption of the current, but may be employed with the so-called "locking" circuits which incorporate auxiliary contacts to relieve the switch contacts of their initial load.

Another object of the invention is to provide means for adjusting the spring reaction member for the purpose of adjusting the action of the armature and contact member carried thereby in order to vary the time "off" after the pilot flame is extinguished.

Another object is to provide an armature assembly which, if the switch is jolted or dropped, prevents disengagement of the switch contacts.

Further objects and advantages of the invention will be apparent from the following detailed description taken in connection with the accompanying drawings, in which:

45 Figure 1 is a front elevational view of a form of thermoelectric switch embodying the present invention;

Figure 2 is a vertical section taken on the line 2—2 of Figure 1;

50 Figure 3 is a horizontal section taken on the line 3—3 of Figure 2;

Figure 4 is a vertical section taken on the line 4—4 of Figure 2;

55 Figure 5 is a fragmentary view showing the reaction spring member and armature system

employed in the embodiment of the invention shown in Figures 1 to 4, inclusive; and

Figure 6 is a fragmentary sectional view through the terminal member for the leads of the thermocouple.

The form of instrument shown in Figures 1 to 5, inclusive, comprises a thermoelectric switch base 180 and a metal box 181 secured thereto by bolt means at 192.

The U-shaped magnet 183 is secured at 184 to one side of the box 181. One end of the coil 185 is electrically connected to the box 181 at 186, and the opposite end of the coil is electrically connected to a terminal plug 187. The plug 187 is insulated from the sleeve 188 by insulation at 189. The plug 187 has an upwardly extending reduced stem which passes up through reenforcing washers 191 on opposite sides of the adjacent end of the ribbon-like member forming the coil 185, and is riveted over at 192. Insulation is provided at 190 between the sleeve 188 and the connected end of the coil 185.

The thermocouple terminal comprises a terminal member 193 fixed on the bared end of the thermocouple lead wire 194 (Figure 6), and a terminal member 195 surrounds and makes contact with the thermocouple lead tube 196. The lead wire 194 and lead tube 196 are insulated from each other at 197, and the terminal member 193 is insulated from the terminal member 195 at 198. The insulation at 198 and terminal member 195 are interlocked at 199, and the union or coupling member 200 binds the parts firmly together with the conical tip of the terminal member 193 in good electrical contact with the corresponding seat in the plug 187 and with the lead wire connected to one end of the coil 185 and the lead tube 196 connected to the other end of the coil through the box 181.

A quick detachable connection is thus provided between the leads of the thermocouple and the coil 185 of the electromagnet. The thermocouple leads are disconnected from and connected to the coil terminal by the simple expedient of removing and applying the union or coupling member 200.

The threaded shanks of contacts 205 and 206 have threaded engagement with metallic connector pieces 207 mounted upon and secured at 208 to insulating terminal blocks 209. These blocks 209 are secured at 210 over openings 211 in the opposite side walls of the box 181. Each connector piece 207 has a terminal screw 214 in threaded engagement therewith for connecting the circuit conductors to the connector pieces, and thereby to the contacts 205 and 206, respectively. One of the circuit conductors is shown at 16' and the other circuit conductor is shown at 23' in Figure 1, the conductor 16' being connected to the terminal screw 214 for the contact 205, and the conductor 23' being connected to the terminal screw 214 for the opposite contact 206.

The contact arm 220, which carries the contact member 221, is secured at 222 to the insulating member 223. This insulating member in turn is secured at 224 to the armature arm 225. The contact arm 220 is connected by a conductor 226 to a connector piece 227 mounted on an insulating terminal block 228 at the front of the box 181. The connector piece 227 is electrically connected to an externally disposed connector piece 230 (Figure 1) which is provided with a terminal screw 231 for connecting a lead 75

conductor 36' to the contact arm 220. The opening in the front of the box 181 over which the insulating block 228 is secured is indicated at 234.

5 The armature arm 225 is secured by lugs 240 to the armature 241 which is fulcrumed at 242 on the lower edges of the outer ends of the legs of the magnet 183. The spring member 244 is loosely mounted, adjacent its lower end, on two supporting and guide pins 244a, as will be clear from Figures 2, 4, and 5 of the drawings, and tends to force the armature assembly clockwise (Figure 4) about the fulcrum 242 to engage contact 221 with contact 206 when the coil 185 is deenergized. When the coil 185 is energized, the magnet 183 pulls the armature to the minimum gap position toward the pole faces of the magnet, and thereby moves the contact 221 out of engagement with the contact 206 and into engagement with the contact 205, and holds the same in this position as long as the pilot flame is burning.

The sides of the spring member 244 have slots 246 in which lugs 247 on the armature arm 225 engage to interlock the armature arm and spring reaction member against relative longitudinal movement. At its lower end, the spring reaction member 244 bears against the inner pointed end of an abutment member in the form of a screw 250 threaded through the adjacent side wall of the box 181. The screw 250 is adjustable to adjust the tension of the spring member 244 and, thereby, the time "off" after the pilot flame is extinguished. The armature 241 is shown in Figure 4 in minimum gap position relative to the pole faces of the magnet 183 and with the contact 221 in engagement with the contact 205, whereas in Figure 5 the armature is shown separated from the pole faces of the magnet 183 to maximum gap position and with the contact 221 in engagement with the contact 206.

The movement is relatively slight, and the structure described not only holds the armature against the magnet when the coil is energized, but moves the armature from maximum armature gap position to engagement with the magnet by the energization of the coil by the relatively weak electromotive force set up by the heat of the flame on the thermocouple.

The thermocouple 30, which has the hot junction 31 and the usual cold junction, may be mounted as shown in Figure 1 on a bracket or other suitable support 260 by means of a tubular nut 262 having threaded engagement with the bracket or support 260, and cooperating with the tapered surface of an enlargement 264 on the thermocouple.

The outer exposed surfaces of the insulating terminal blocks 209 (Figure 1) may be differently colored or differently marked at the respective contacts to facilitate proper connection of the respective conductors therewith. In the case of coloring, the outer face of the insulation at one contact may be colored red, the outer face of the corresponding insulating member at another contact may be colored blue, and the outer exposed face of the insulating member at the third contact means may be colored white. Any other different colorings or other suitable markings may, of course, be employed.

I do not intend to be limited to the precise details shown or described.

I claim:

1. In a device of the character described, an electromagnet comprising a frame having pole

ends, a leaf spring supported at one end for movement toward and away from the pole ends of said frame, an armature carried by said spring remote from said one end thereof fulcrumed at one edge on said pole ends for rocking movement toward and away from the latter and having limited movement away from said pole ends, said spring urging said armature away from said pole ends, and means cooperating with said spring for adjusting said end thereof toward and away from said pole ends and thereby varying the tension of said spring effective for urging said armature away from said pole ends.

2. In a device of the character described, an electromagnet comprising a frame having pole ends, a leaf spring supported at one end for movement toward and away from the pole ends of said frame, an armature carried by said spring remote from said one end thereof fulcrumed at one edge on said pole ends for rocking movement toward and away from the latter and having limited movement away from said pole ends, and an abutment member contacting the face of said spring away from said pole ends, said abutment member being adjustable for varying the tension

10 of said spring effective for urging said armature away from said pole ends.

3. In a device of the character described, a supporting structure comprising two opposite walls, 5 an electromagnet mounted on one of said walls and extending inward therefrom toward the other wall, said electromagnet comprising a frame having pole ends facing toward said other wall, a leaf spring extending downward below said pole ends adjacent said other wall, means carried by said other wall adjacent the lower end of said spring loosely supporting the latter for movement toward and away from said other wall, an armature carried by said spring at the upper portion thereof fulcrumed at its lower edge on said pole ends for rocking toward and away from the latter and having limited movement away from said pole ends, and an abutment member carried by said other wall contacting the outer face of said spring 20 adjacent the lower end thereof, said abutment member being adjustable for varying the tension of said spring effective for urging said armature away from said pole ends.

THEODORE A. WETZEL.
